Primary Examiner — Mary Ann Calabrese*Assistant Examiner* — Hillary Catherine Shepard(74) Attorney, Agent, or Firm — Daniel M. Cohn; Howard M. Cohn(57) CLAIM

The ornamental design for an air sofa lounger as shown and described.

DESCRIPTION

FIG. 1 is a perspective view of an air sofa lounger;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is an enlarged view of portion 8 shown in FIG. 1. The broken lines in the drawings depict portions of the air sofa lounger that form no part of the claimed design. The dot-dash broken lines represent boundaries of the enlarged portions and form no part of the claimed design.

1 Claim, 8 Drawing Sheets(56)
